UNITED STATES PATENT OFFICE.

SAMUEL CABOT, JR., OF BOSTON, MASSACHUSETTS.

GAS-PRESSURE REGULATOR.

SPECIFICATION forming part of Letters Patent No. 315,717, dated April 1st, 1885.

Application filed January 7, 1885. (No model.)

To all whom it may concern:

Be it known that I, SAMUEL CABOT, Jr., a citizen of the United States, residing at Boston, in the county of Suffolk and State of Massachusetts, have invented certain new and useful Improvements in Gas-Pressure Regulators, of which the following is a specification, reference being had therein to the accompanying drawings.

10 This invention is related to a class of machines which are used under a great variety of conditions for controlling and modifying the pressure of air and gases, and its special function is to accomplish for gases moving 15 through tubes the continuous and uniform reduction of very high pressures to such as are but slightly above that of the atmosphere by means which are simple and inexpensive.

In the drawings forming part of this specification, Figure 1 shows in plan the apparatus employed. Fig. 2 is a vertical cross-section of the same on line *x x*, showing parts of the apparatus in elevation. Fig. 3 is an elevation from the same point of view as Fig. 2, but 25 the passage of gas through the apparatus is interrupted. Fig. 4 shows part of the delivery system from such a pressure-regulator, with a modified position for the safety-valve.

This invention consists of an inverted vessel, *a*, which floats in mercury (represented by the horizontal shading at *b*) contained in the annular chamber which forms part of the bed-plate *c*. In use this bed-plate rests upon some convenient and firm support. The gas 30 under high pressure enters the apparatus from a suitable service-pipe at *d*, passes through the fixed tube *e*, and (when open) through the stop-cock *f*, then through *e'*, from which it finally flows, relieved of pressure, to a suitable 35 system of tubing which connects at *g*, (see Fig. 4,) and conveys it to the places where it may be required for lighting, heating, the generation of power, and for other purposes. It will be seen that the tube *e'* also connects with the 40 inclosed chamber *S* within the inverted vessel *a* by means of the small closed channel *h*, (shown in dotted lines, and bored or otherwise formed in the bed-plate *c*.) The reduction of pressure in the tube *e'*, and all its subsequent 45 connections, is effected by the cock *f*. In the 50

position shown in Fig. 2 this cock is fully open, in which case a pressure will be instantly established within the inverted vessel *a*, which will rise in consequence until its weight balances the pressure which lifts it. But this 55 movement of the vessel *a* tends to close the cock *f* through the intervention of the link *i*, which carries with it the plug of said cock. The accession of force lifting the vessel *a* will diminish accordingly and cease altogether 60 whenever the passage of gas is completely cut off at *f*.

In Fig. 3 the vessel *a* is raised to the fullest extent which the particular construction shown admits of, for the parallel link *j* in it 65 is in contact with the adjustable stop *k*. In this position the cock *f* is completely closed. Lower positions of *a* let some gas pass at its high initial pressure into the tube *e'*, and the plug of the cock *f* will stay at rest only so long 70 as that pressure and the abstraction of gas for use from any part of the system of distribution remain constant. Whenever either of these factors are changed, a corresponding change will take place in the position of *a*, 75 and, as a consequence, in the size of the open passage through the cock *f*. The result will be an automatic adjustment and restoration of a constant pressure in the gas filling the distributing system. The amount of that press- 80 ure will depend, essentially, upon the weight of the vessel *a* in relation to the area of its horizontal cross-section, and, as the weighting of *a* is under easy control, any desired pressure may be maintained in the pipes 85 conveying the gas from the regulator to the several places where it is consumed.

Devices such as that described are theoretically correct in action if the assumption be made that all the work on the apparatus is 90 perfectly executed, and the latter sufficiently large to furnish the power required to overcome the friction of the moving parts.

In practice, I have found certain difficulties to present themselves when the original elastic 95 force of the gas is very great—say, six, eight, or ten atmospheres, pressures not unfrequently met with in gas from natural wells. When such have to be reduced to those that are suitable for dwelling-house illumination or heat- 100

ing, the difference is so great that it is impossible at moderate cost to construct a cock or valve for the position occupied by *f* which will remain perfectly tight after it is closed. The 5 small quantities of gas which then pass an ordinary cock or valve continue to lift the vessel *a* until the stop *k* is reached; or, if there be no stop, until the mercurial column balances the pressure within. In either case, as the 10 leakage of gas goes on, the vessel *a* ceases to rise, but the gas blows through the mercury, disintegrating it and throwing it about in small quantities in a wasteful way, injurious to the surroundings and destructive of the apparatus itself, which should work well and reliably at all times without care or attention. If an effort be made to produce a perfect cock 15 or valve to fill the place at *f*, it will be found that frictional resistance, due to close and tight-fitting surfaces, will have to be overcome, and, in consequence, the size of the floating vessel *a* must be increased to gain commensurate power. This adds largely to the cost of every part, and especially that of 20 the mercury, whereas when an ordinary cock or valve can be used to perform the functions of *f* the cost of the whole apparatus is small.

In my invention I attach to the inverted receiver *a* a small safety-valve, *l*, opening outward and held in position by a spring or weight, or both, as in Figs. 2 and 3, in which the compression of the spring *m* by a nut upon the valve-stem gives the necessary adjustability. This valve is made to blow off at a 30 pressure in excess of that required for the automatic complete closing of the cock *f*, but less than that which the gas must have to blow through the mercury.

By virtue of this device the imperfections 40 of the cock or valve at *f* give rise only to small leakages from the valve *l*, which in most cases is productive of no injury or inconvenience, and thus my invention secures the automatic regulation of gas or other aeriform 45 fluids at small cost and by means of apparatus occupying but little space and requiring no attention.

It is plain that the safety-valve which I use 50 in combination with the regulating apparatus (without appreciably affecting the result) may be applied to any part of the delivery system which is in direct and free communication with the floating vessel *a*. When, therefore, the locality in which a gas-regulator has to be placed 55 makes it undesirable that a leakage of gas should issue from it, I remove the safety-valve to some convenient part of the tubing used for

delivery, as shown in Fig. 4, where the slight escape of gas is not offensive, or where it can be easily removed by establishing a suitable 60 draft. In this case *l'* represents the valve adjustably loaded by means of a lever and weight and directly connected with the interior of the floating vessel by the tubes *n*.

I am aware that the automatic regulation 65 of gas-pressure has been more or less perfectly accomplished by the rise and fall of inverted floating vessels, such as that described herein, by elastic diaphragms, and by expandable bellows-receptacles and similar devices 70 exposed to the force of the gas, which fills the distributing system, and I do not claim any such contrivances, broadly.

I am also aware that other fluids can be used as well as mercury, and I do not, therefore, lay 75 claim to any particular construction of that part of the apparatus, or of the safety-valve, which in my invention disposes of the gas which leaks into the regulator after its abstraction by the distributing system has ceased. So

What I do claim, and desire to secure by Letters Patent, is—

1. A gas-regulator provided with a safety-valve communicating with the reduced pressure-chamber, substantially as and for the purpose described.

2. In a gas-regulator, the combination of the cock *f*, the inverted floating vessel *a*, and the safety-valve *l*, as and for the purpose described.

3. In a gas-regulator provided with a mercury-basin and a floating vessel, a safety-valve or equivalent device communicating with the low-pressure chamber therein, whereby leakages of gas into the latter may escape to the 95 open air instead of blowing through said mercury, substantially as and for the purpose described.

4. In a gas-regulator, the combination, with a low-pressure chamber, of a safety-valve arranged upon the distribution service-pipe which communicates with said chamber, substantially as and for the purpose described.

5. As a new article of manufacture, a floating vessel for a gas-regulator provided with a 100 safety-valve opening outward, substantially as and for the purpose described.

In testimony whereof I affix my signature in presence of two witnesses.

SAMUEL CABOT, JR.
